5 Claims. (Cl. 162—352)

This invention relates to Fourdrinier paper making machines and more particularly to improved liquid drainage apparatus. 10

The forming of a pulp web in a Fourdrinier machine is made in such a way that a mixture of water and fibre flows out of a head box to a moving endless wire screen, the water being then drained from the mixture as it travels on the wire to a point where it is finally compacted by the application of high vacuum and the web is strong enough to be removed from the wire.

In this process it is essential that the stock be drained adequately prior to its final compaction, otherwise the best results in paper strength and quality are not obtained because the fibres of the stock tend to lump together in a non-uniform paper formation. However, it has been found that with adequate drainage a dilute stock is desirable because it gives a more uniform formation of the paper fibres with resultant increase in strength and quality of the paper but the use of such stock accentuates the problem of such drainage and proposals have been made to increase the hydrostatic head on the wire during the early part of its travel.

To this end, high vacuum boxes have been employed but these have the disadvantage that the drag imposed on the wire results in added wear and furthermore sagging of the stock on the wire takes place, with resultant non-uniformity of the thickness of the paper unless table rolls are supplied underneath the wire to give the requisite support. Unfortunately, such table rolls themselves create a problem of throwback of the liquid carried around in the rolls causing disruption of the partially orientated fibres thus impairing the drainage and hence the quality of the finished paper. Furthermore, such high vacuum suction arrangements are costly of construction because complicated and expensive sealing mechanisms are required.

Alternatively, attempts have been made to employ low suction vacuum boxes operating directly under the wire, but this again suffers in the main from the difficulty of providing a constant seal between the boxes and the wire.

The result of the difficulties experienced with high and low vacuum boxes has been a general reliance on free gravity drainage in commercial machines in the early stage of travel of the stock on the wire, but it will be appreciated that if such gravity drainage is just adequate with a particular dilution of stock the only method of achieving the same adequacy if a more dilute stock is used with the intention of producing a higher quality of paper is to reduce the rate of movement of the wire. This curtailment of the speed of the wire means that the rate of production is adversely affected. In the interests of flexibility and maximum efficiency it would be desirable to introduce simple and inexpensive means which would augment the gravity drainage when necessary.

To this end a member or deflector is positioned under the wire inclined in a direction corresponding to the travel of the stock, the upper end of the deflector being substantially in a plane with the underside of the wire whereby hydrodynamic suction takes place in the zone subtended by the wire and the member resulting in withdrawal of liquid from the stock in a flow downward over the upper surface of the deflector. The natural extent of the hydrodynamic suction zone is determined by the

2

extent to which turbulence can be delayed or "laminar" flow preserved in the liquid flowing on this upper surface, the term "laminar" flow designating regular and smooth steady motions which do not show the irregular fluctuations characteristic of the turbulent flows, the existence of which will depend on differences in the rate of travel from the outside to the inside within the liquid flow.

The improvement of the invention consists in providing positive means to energize the static or boundary layer of the liquid adjacent to the upper surface of the deflector to give it motion thus delaying separation of the faster moving liquid further removed from the upper surface of the deflector. By this means the distance of laminar flow on the upper surface of the deflector is extended and the zone of hydrodynamic suction of the stock on the wire is increased thereby augmenting the drainage.

It is then an object of this invention to provide apparatus whereby the length of stock subjected to hydrodynamic drainage may be reduced while giving the required result of high strength and quality of the drained web, the apparatus being simple and inexpensive.

This and other objects, features and advantages of this invention will become apparent to one skilled in the art from the following description of the embodiment 25 illustrated in the accompanying drawings.

FIGURE 1 is an elevational diagrammatic view of a preferred embodiment of the invention showing parts in vertical section;

FIGURE 2 is an elevational diagrammatic view of 30 another preferred embodiment of the invention with parts in vertical section.

As shown in the drawings:

In the embodiment shown in FIGURE 1 a travelling forming wire 10 carries stock 11 thereon. A deflector 12 having its upper part inclined in a direction corresponding to the travel of the stock 11, supports the wire 10, the lower part of the deflector 12 being carried by supports 13 attached to a base 14. The length and relative position of the supports 13 are adjustable so that the inclination of the deflector 12 in relation to the wire 10 may be varied. The upper end of the deflector 12 is substantially in a plane with the underside of the wire 10 and water extracted from the stock 11 by hydrodynamic suction flows over the upper surface of the deflector 12. At the lower end of the deflector 12 a roll 15 is positioned so that its upper surface and the upper surface of the deflector 12 form a substantial continuous surface, the aperture 16 between the lower end of the deflector 12 and the surface of the roll 15 being just large enough to ensure that there is no frictional engagement. The roll 15 is supported through its axle 17 by means of members 18 attached to the base 14; the length of these members 18, as also their position on the base 14, can be varied to alter the position of the roll 15 along with any alteration in the inclination of the deflector 12 so that an upper part of the surface of roll 15 always provides a substantially continuous surface with the upper surface of the deflector 12. Drive means, not shown, are provided to rotate the roll 15 in a direction corresponding to the movement of the wire 10 and it is rotated at a velocity whereby it provides a downward and forward drag on the laminar fluid flow the upper surface of the deflector 12.

The speed of rotation of the roll 15 constitutes a control means for extending the natural hydrodynamic suction zone created between the wire 10 and the deflector 12, the extent of this natural zone in cross section being indicated by the curved line A. The extension of this zone by means of rotation of the roll 15 can be best appreciated by considering the theory of fluid film, this being introduced for the purpose of understanding and not by way of limitation. It is generally recognized that

a fluid flowing along a surface does not move at a uniform rate at all points in a cross section normal to the surface of the film. On the contrary, the film adjacent to the surface, known as the "boundary layer" is practically static; the film next to this boundary layer moves slightly more rapidly and so on until a point is quickly reached in the flow where the fluid moves with practically no friction. This difference in speed between the frictionless flow of the fluid and the boundary layer increases the further the fluid travels along an inclined surface of the deflector 12 and there comes a point when the difference in speed is sufficient to create turbulence and eventual separation of the films. At this point the pull of the fluid travelling along the inclined surface of the deflector 12 on the hydrodynamic suction zone will be disrupted and this is the reason for the limitation in the amount of dewatering of the stock 11 which takes places by gravity suction.

The rotation of the roll 15 exerts a downward and forward movement to the boundary layer of the liquid flowing along the upper surface of the deflector 12 and it follows from the above explanation that this will aid the persistence of laminar flow of the liquid if the boundary layer of the fluid film is effectively energised. In this way separation of the films will be delayed extending the zone of hydrodynamic suction to B¹ and B², etc., depending on the speed of rotation of the roll 15 and a greater length of the stock 11 on the wire 10 will be subjected to dewatering.

In operation the extent of the zone of the hydrodynamic suction subtended between the deflector 12 and the wire 10 will be determined visually and the position of the roll 15 and the angle of the deflector 12 will be adjusted until the upper surface of the roll 15 enters the zone. The roll 15 will then be rotated at the desired speed to energize the static boundary layer of the flowing liquid on the deflector 12 thus extending the hydrodynamic suction zone and augmenting the dewatering of the stock 11; the extent of the suction zone may be increased by rotating the roll 15 at a higher speed.

In the embodiment shown in FIGURE 2 the deflector 12 has apertures 19 connecting the upper and lower surfaces which are inclined in a forward and downward direction in relation to the movement of the wire 10. A water supply 20 under pressure is directed against the under surface of the deflector 12 and this flow of water through the apertures 19 to the upper surface of the deflector 12 provides a pressure differential which energizes the static boundary layer, thus extending the zone of suction and augmenting the dewatering of the stock 11.

It will be understood that modification and variation may be effected without departing from the scope of the novel concepts of the instant invention.

What I claim is:

1. Dewatering apparatus for use with a machine of

40

35

45

50

55

the Fourdrinier type having a screen arranged to be driven in a predetermined direction, comprising: deflector means for mounting beneath the screen, to extend transversely in relation to said predetermined direction and having an upper surface and a lower surface, the upper edge of said upper surface of the deflector means contacting the under surface of the screen for at least a portion of its length, said upper surface diverging downwardly from the screen in said predetermined direction to position the lower edge thereof from the screen, said deflector means including energizing means having a surface moving in close proximity with said lower edge to energize liquid flowing from the screen over the deflector means whereby the hydrodynamic suction effect between said deflector means and the screen is improved.

2. A dewatering apparatus as claimed in claim 1 wherein said energizing means comprises a roll positioned in close running relation to the lower edge of said deflector, and drive means to rotate said roll.

3. Dewatering apparatus for use with a machine of the Fourdrinier type having a screen arranged to be driven in a predetermined direction, comprising: deflector means for mounting beneath the screen, to extend transversely in relation to said predetermined direction and having an upper surface and a lower surface, the upper edge of said upper surface of the deflector means contacting the under surface of the screen for at least a portion of its length, said upper surface diverging downwardly from the screen in said predetermined direction to position the lower edge thereof from the screen, a lower portion of the upper surface of said deflection means including the upper surface of a roll in close conformity with the upper portion of the deflection means to provide a substantially continuous surface, and drive means for rotating the roll in a direction corresponding with said predetermined screen direction whereby the rotation of said roll energizes liquid flowing from the screen over the deflection means, to improve the hydrodynamic suction exerted on said screen.

4. Dewatering apparatus as claimed in claim 3 including adjustable mounting means for adjusting the mounting of said deflector and said roll relative to said screen.

5. Dewatering apparatus as claimed in claim 4 wherein said adjustable mounting means permits adjustment of said roll relative to the upper portion of said deflector means.
